UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

SHEET-METAL BOX.

1,181,907.

Specification of Letters Patent. Patented May 2, 1916.

Original application filed July 11, 1914, Serial No. 850,289. Divided and this application filed August 31, 1915. Serial No. 48,163.

To all whom it may concern:

Be it known that I, GEORGE A. LONG, a citizen of the United States, residing at Hartford, in the county of Hartford and 5 State of Connecticut, have invented certain new and useful Improvements in Sheet-Metal Boxes, of which the following is a specification.

This invention relates to sheet metal 10 boxes.

The present application is a division of an application filed by me July 11, 1914, Serial No. 850,289.

While a box involving my invention is 15 susceptible of general use, it is of particular advantage when used in combination with or as part of a telephone pay station; in this particular use it is adapted to inclose certain of the elements of such machine.

20 There are generally speaking three different types of boxes employed for telephone pay stations, one of those being cast. This is the kind of box which is most commonly used. It is heavy and cumbersome and can be easily broken to rob the instrument.

25 A box made of sheet metal is the very best kind in that it possesses maximum strength with minimum weight. There are two types of sheet metal boxes now in use, one so costly to manufacture that its use is practically prohibitive. The other box involves the use of rivets in its make-up, but one of this character has disadvantages owing to the presence of joints into which an implement can be readily inserted to pry the box 30 open. The rivets are also objectionable in that they affect the resonant connection between the signals and the telephone transmitter.

35 I provide a box possessing the two important points, namely maximum strength and extreme lightness, and in addition obviate the necessity of rivets and the necessity of any annealing operations.

40 In the drawings accompanying and forming part of the present specification I have shown in detail one convenient form of embodiment of the invention, which will be set forth in detail in the following description.

I do not, however, limit myself to this particular disclosure; I may depart therefrom in several respects within the scope of the invention defined by the claims following said description.

45 As I have already noted the present case is a division of a prior application already identified, and the drawings mentioned are duplicates of those of the prior application. These drawings naturally illustrate how the method of the other can be carried into effect. Of course, the method is not claimed herein.

50 Referring to said drawings: Figure 1 is a flat or developed view of the blank for the upper section or half of the box. Fig. 55 2 is a central sectional view of the same, showing certain bends made in said blank. Fig. 3 is a vertical sectional view of the said upper section of the box in practically completed condition. Fig. 4 is a perspective 60 view of the same. Fig. 5 is a detail view of a filling piece or corner blank, and Figs. 6 and 7 are front and side elevations of the same in finished form. Fig. 8 is a flat or developed view of the blank of the body 65 portion of the lower section or half of the box. Fig. 9 is a front view of the main portion showing the initial operations on said body portion blanks. Fig. 10 is a front 70 view of the body portion of the lower box half in finished form. Fig. 11 is a perspective view of the same. Fig. 12 is a flat or developed view of the blank for the front or face portion of the lower box half. Fig. 13 is a sectional view of the shaped up blank 75 of Fig. 12, and Fig. 14 is a like view of the finished face portion. Fig. 15 is a perspective view of the front or face portion of the lower box half in finished form. Fig. 16 is a perspective view of the completed 80 box.

85 Like characters refer to like parts throughout the several views, which it will be noticed are on different scales.

90 A telephone pay station box comprises as a rule what is known as a "lower half" as 2 and an "upper half" as 3, (Fig. 16) and it is one of the primary purposes of the method

to form these halves in a simple, inexpensive and rapid manner from sheet metal.

In Fig. 1 I have shown a flat blank denoted in a general way by 4, from which the upper half 3 can be conveniently made. This blank can be cut by the aid of suitable dies or otherwise, from sheet stock of the requisite grade or thickness in such manner as to present a main portion 5 and a supplemental portion 6 projecting substantially centrally in the form of a wing from the upper edge of said main portion. In the lower edge of the main portion 5 are cut two approximately rectangular notches 7 and 8 which are practically centrally intersected by the fold or bend lines 9 and 10 hereinafter referred to, and which notches or slots 7 and 8 as will also hereinafter appear are adapted to receive filling or corner pieces preferably electrically welded in place, although said filling pieces might be otherwise secured in position. When these filling pieces are secured in position by welding or otherwise, their outer surfaces are practically flush with the outer surface of the upper half or box section 3; as a matter of fact in practice when the said upper half is japanned or otherwise treated, the joints between the filling pieces and the box section cannot be seen. The fold lines 9 and 10 are continued across the wing or flap 6. In one of the side edges of the main portion 5 are formed duplicate apertures 11 and 12 which in the finished box, are adapted to receive fastenings by which the back (not shown) of said box can be held in place. In the wing or flap 6 is formed an elongated slot 13 which receives the usual "coin gage" as it is known. The sides of the wing first diverge outwardly as at 14 and 15 upon equal angles beyond which said sides are straight and in parallelism as at 16 and 17. Initially by the aid of suitable dies in a press of proper kind, the wing or flange 6 is bent on itself along its sides to produce the duplicate right angular flanges 18, the folds or bends being on the lines 9 and 10, said flanges 18 as will be understood, extending inwardly. Subsequent to this the upper portion of the wing 6 is bent inwardly as at 19 along a line as 20, which line intersects the points where the angular portions 14 and 15 merge respectively in the parallel portions 16 and 17. After the wing is bent on itself on said line 20 to produce the slope 21, said wing as a whole is bent down at right angles to and where it joins the main portion 5, this particular operation drawing the side edges of the flanges 18 into line as illustrated in Fig. 3. Succeeding this action the main portion 5 is bent rearwardly at opposite sides on the lines 9 and 10 to form the sides 22 of the upper half 3, the upper edges of said sides 22 being thus brought into contact or abutment with the straight

lower edges of the flanges 18 at which time the sides 22 will be welded or otherwise rigidly united to said flanges 18 along the abutting edges of said parts. While I prefer to electrically weld said sides 22 and flanges 18, it is conceivable that their union can be secured in other ways. At some stage of the process and preferably while the blank 4 is flat the lower notched edge thereof is externally beaded in an outward direction. By the formation of the notches 7 and 8 before the main portion is bent, I find that when the lateral portions of said main portion are folded back to produce the sides 22, there is no tendency to distort or otherwise injure the projecting lower beaded portion of the upper half. In Fig. 4 the upper half is shown practically completed, the only thing remaining to be done being to insert filling pieces such as the frusto-angular parts 23 in the notches 7 and 8, the filling pieces being shaped to agree with the notches and consequently as their designation implies, completely filling the notches and being preferably electrically welded therein, although as will be inferred, they might be held in place in some other way. In Fig. 5 I have shown the blank 24 on one of these filling pieces, and this blank by the aid of suitable dies and other instrumentalities will be shaped up to conform in external appearance to or match the beaded lower part of the upper half 3.

In a telephone pay station the upper half 3 consisting of a front, two sides and a top, 100 contains the chute and the signal mechanism. The flanges 18 to which I have referred, depend from the top of the half or section 3. The lower half or section 2 contains the coin-box. Said lower half comprises a body portion as 25 (Fig. 11) and a front or facing portion as 26. In Figs. 8 and 12 I have shown the blanks from which said body portion 25 and facing portion 26 can be respectively made. The body portion 110 blank denoted in a general way by 27, in Fig. 8, is cut by any suitable dies or otherwise, from sheet metal and as will herein-after appear the end portions are bent upward at right angles to the intermediate 115 portion along the lines 28 and 29 from which it will be clear that the main part of the body blank is made up of three approximately equal portions each provided with a projecting wing 30 all of said wings 120 being alike. In addition to these wings 30 the ends of the blank 27 have duplicate wings 31. It will be seen that the side edges of the wings 30 are on outwardly converging equal angles. It should be also noticed 125 that the ends of the wings 31 are on similar angles. On the first operation on the blank 27 all of the wings 30 and 31 are bent up at right angles to the body of said blank which brings the rear beveled ends of the 130

wings 31 against the beveled outer ends of the outer wings 30. On this operation the ribs 33 can be formed on the upper side of the blank 27, these ribs 33 constituting a 5 guide for the money-drawer which I have not shown. The abutting ends of the wings 31 and the outer wings 30 can now be electrically welded or otherwise secured together. After this operation the end portions of the blank 27 are brought up at right 10 angles to the intermediate portion on the lines 28 and 29 which results in bringing the beveled ends of the intermediate wing 30 into abutment against the adjacent beveled 15 ends of the two outside wings 30, and when this is accomplished, said wings can be electrically welded or otherwise conveniently united. This makes the body portion 25 of the lower half 2.

20 In Fig. 12 I have shown the blank 34 from which the facing or front 26 of the lower half 2 can be made, said blank 34 like the others being cut by the aid of suitable dies or otherwise, from flat sheet stock. When 25 the blank 34 is stamped out, it has preferably simultaneously cut therein the comparatively-large opening 35 and the smaller opening or slot 36. It is through this opening 35 that the coin drawer is inserted, while 30 the opening or slot 36 is intended for the passage of coins which may be returned to a subscriber in case he fails to obtain a connection. On the inner wall of the opening 35 is a wing 37 which is adapted to be bent 35 back at some stage in the method, to constitute a partition for separating the slot 36 from the coin-drawer opening 35. On the top wall of said opening 35 is a notched 40 projection or lug 38 which at the same time that the wing 37 is bent back, can be also bent back, to present a keeper for the bolt of the lock of the money-drawer. On the bottom of the blank 34 is a substantially 45 rectangular wing 39 while on the sides are wings 40 and 41, the lower edges of the wings 41 being at right angles to the vertical axis of the blank 34, while the upper edges of said wings 40 and 41 are along outwardly-diverging angles. On the top of 50 the blank 34 is the wing 42, the sides of which are first straight and in parallelism and are then along outwardly-converging similar angles. The wings 39, 40 and 41 are bent at right angles to the body of the 55 blank 34, while the lower portion of the wing is bent at a steep angle to the body. This brings the terminals of the wings 40 and 41 and the upper angular ends of the wings 40 and 41 against the parallel end 60 portions of the steep sloping part of the wing 42 and where the several wings are brought together, they are electrically welded or otherwise united as before described. The upper portion 43 of the wing 65 42 is bent at right angles to the body of the

blank 34 and all the various operations thus far described in connection with said blank 34 can be accomplished simultaneously to produce the article shown in Fig. 13. After the step thus described has been performed, 70 the wings 37 and 38 can be bent at right angles and at the same time there may be formed around the opening 35 the rabbet 44 as shown in Fig. 14, to receive the front of the money-drawer. This in fact finishes the 75 face portion 26. The edges of the wings 39, 40, 41 and 43 can then be fitted against the front edge of the body portion 25 and the two electrically welded or otherwise suitably secured together. To facilitate welding I may if desired upset the metal along 80 the parts which are to be thus joined, the upset portions being preferably coextensive with the butt joints. These upset portions when fused flow into the cracks at the butt 85 joints.

What I claim is:

1. A sheet metal box section having a front, sides and a top, the top having one portion at an inclination and another approximately horizontally disposed, said top having portions bent downward from the sides thereof and rigidly united with the upper edges of the sides of the box section along straight lines at substantially right 90 angles to the longitudinal axis of the box section, the inclined portion being slotted. 95

2. A sheet metal box section having a front, sides and a top, the top having one portion at an inclination and another horizontally disposed, said top also having its sides bent downward and welded with the upper edges of the first mentioned sides and the inclined portion being slotted. 100

3. A sheet metal box section having a front, sides and a top, said section being beaded at its lower portion and notched in its lower edge at approximately the junction of the sides with the front, and filling pieces welded in the notches and conforming to 105 the shape of the beading, said top having its front portion at an inclination and its rear portion approximately horizontally disposed, the sides of the top being bent downward and being welded to the first mentioned sides, said inclined portion being longitudinally slotted. 110

4. A sheet metal box section having a front and sides extending rearwardly from the front, the box section being notched in 120 its lower edge and the junction lines between the front and the respective sides extending through the notches, and filling pieces rigidly mounted in the notches, the lower edge of the box section being beaded 125 and the filling pieces being shaped to conform to the shape of the beading.

5. A sheet metal box section having a front, sides and top, the top having the front portion at an inclination and the rear 130

portion approximately horizontally disposed, said top having portions bent down from the sides thereof and rigidly united with the upper edges of the sides of said
5 box section along straight lines approximately at a right angle to the longitudinal axis of the box section.

In testimony whereof I affix my signature in presence of two witnesses.

GEORGE A. LONG.
